UNITED STATES PATENT OFFICE.

CHARLES C. BARBER, OF FREEPORT, NEW YORK, ASSIGNOR TO WESTERN ELECTRIC COMPANY, INCORPORATED, OF NEW YORK, N. Y., A CORPORATION OF NEW YORK.

OIL PUMP.

Application filed May 5, 1922. Serial No. 558,769.

To all whom it may concern:

Be it known that I, CHARLES C. BARBER, a citizen of the United States, residing at Freeport, Long Island, in the county of

Queens, State of New York, have invented certain new and useful Improvements in Oil Pumps, of which the following is a full, clear, concise, and exact description.

This invention relates to gear pumps and 10 more particularly to pumps wherein a train of gears is driven through an oil level, and wherein the use of external conduits is eliminated.

An object of this invention is to provide 15 a pump, simple in construction, reliable in operation, and wherein the objectionable feature of foaming (air imprisonment) is obviated.

Another object of this invention is to produce 20 a pump in which the use of external conduits and fittings is eliminated.

Oil foaming, which may be described as an accumulation of air bubbles on the surface of a lubricant, has heretofore been an 25 objectionable feature in pumps of the nature described herein. By introducing means for venting the drive gear chamber, which provides for the complete circulation of air about the drive gears, the device herein disclosed 30 overcomes this objectionable feature and allows the gear train to be driven through the oil level without foaming. The venting of the drive gear chamber is accomplished by providing an idler gear with 35 shoulders so that the air that normally fills the space between adjacent teeth is allowed to pass out from between the teeth and circulate about the sides of the gears rather than become imprisoned in the lubricant. 40 Prior to the use of this feature it was necessary to transmit the motion of the drive gear to the pump gears by means of a length of shaft which passed through the oil level. This necessitated a complicated structure 45 and one that was not readily adaptable for service with all mechanical devices wherein bearings were to be lubricated.

The main castings of the bearing box disclosed in this invention are formed to contain channels and ducts which serve to convey the lubricant from one reservoir to another and to distribute the oil over the bearings to be lubricated. This is an added feature to pumps of this nature in that it does

away with all external conduits and fittings 55 and provides for a simple, compact and reliable structure.

A complete understanding of the invention will be had from the following description of the operation of the gear pump 60 as disclosed in the drawing, in which similar reference characters designate similar parts throughout the several views.

Fig. 1 shows the bearing box with the cover in position; Fig. 2 is a view of the 65 bearing box with the cover removed and the gear train exposed; Fig. 3 is a sectional view along the line 3—3 in Fig. 1; Fig. 4 is a sectional view along the line 4—4 of Fig. 1; Fig. 5 is a sectional view along 70 the line 5—5 in Fig. 4; Fig. 6 is a sectional view along the line 6—6 in Fig. 4.

Shafts 1 and 2, adapted to be driven from any suitable source of power, are housed in bearing box 3. Drive gear 4, located in the 75 drive gear chamber 5 and mounted on the shaft 2, is held in position by an auxiliary end 6 and transmits motion to pump gears 7 through an idler 8. Idler 8 is provided with spacing collars 16 which permit the 80 circulation of air about the gears and prevents its imprisonment within the lubricant. Bearing box 3 is provided with lubricant chambers 10 and 11 and reservoir 9. A vertical channel 12 located in cover 17 connects reservoir 9 with chamber 11 and conveys lubricant from one to the other under the action of the pump gears 7. Communicating ducts 14 and 15 permit the passage 85 of oil from chambers 11 and 10, respectively 90 to the bearings 1 and 2. The cover 17, held in position by retaining screws 18, is provided with pipe plugs 19 and 20 for filling and draining the reservoir 9. A sight 21 is provided to show whether or not the lubricant 95 is being delivered at the top of the bearing box, while sight 22 shows the predetermined maximum and minimum oil levels in reservoir 9.

The following description of the process 100 of lubricating shafts 1 and 2 and their associated bearings will give a clear understanding of the operation and construction of the gear pump disclosed in this invention.

The plug 19 is removed from the cover 17 105 and lubricant is poured into the bearing box filling reservoir 9 to its maximum level, which may be determined by means of the

lower sight 22. The plug 19 is then inserted and the apparatus set in motion. Drive gear 4, mounted on shaft 2, receives power from any suitable source and transmits it to the 5 pump gears 7 through an idler 8. The oil is forced into the orifice 13 and by the continued action of the pump gears 7, is forced through the vertical channel 12 and into the chamber 11, causing the oil level to drop 10 slowly to the running oil level in reservoir 9. This level is approximately at the center of the oil sight 22. The bottom of chamber 11 is saucer-shaped to insure the delivery of oil to duct 14. The duct 14 associates chamber 15 11 with shaft 1 and conveys the lubricant to this shaft and its bearing. Any excess of oil in the chamber 11 overflows and passes to chamber 10 by means of duct 23. The oil passing through duct 14 lubricates shaft 1 20 and then drips into chamber 10 through the openings 24. The oil accumulating in chamber 10 passes through the duct 15 to shaft 2, lubricating its bearing. The excess oil in chamber 10 is passed to reservoir 9 by way 25 of oil passages 25. Some of the oil lubricates shaft 2 and passes to the bearing of the auxiliary end 6 by way of oil grooves 27, whereas the rest drips from bearing 2 and is returned to reservoir 9 through the 30 oil passages 26. That portion of the oil that lubricates the bearing of auxiliary end 6 also returns to reservoir 9 by way of duct 30.

In the foregoing description the complete system of circulation has been shown where- 35 in the lubricant, by the action of a set of pump gears, is forced from a main reservoir or pumping chamber through a series of ducts or channels which are substantially cavities or apertures in the main castings of 40 the bearing box and is distributed over a set of bearings and returned again to the first reservoir or pumping chamber.

What is claimed is:

1. A bearing, a casing integral therewith forming a reservoir and provided with passage-ways communicating with said bearing, a cover for said casing serving as one side wall for said reservoir and provided with a vertical conduit communicating with said reservoir and said passage-ways, pump gears submerged in a lubricant in said reservoir, a drive gear partly submerged and meshing with one of said pump gears, means for driving said drive gear to operate said pump gears whereby the lubricant is forced through said vertical conduit and said passage-ways for lubricating said bearing.
2. A bearing, a casing integral therewith forming a reservoir and provided with passage-ways communicating with said bearing,

a cover for said casing serving as one side wall for said reservoir and provided with a vertical conduit communicating with said reservoir and said passage-ways, pump gears submerged in a lubricant in said reservoir to circulate the lubricant through the vertical conduit and passage-ways, means for driving said gears, said means being adapted to extend through the surface of the lubricant, and means associated with said driving means to allow the escape of air. 65

3. A bearing, a casing integral therewith forming a reservoir and provided with passage-ways communicating with said bearing, a cover for said casing serving as one side wall for said reservoir and provided with a vertical conduit communicating with said reservoir and said passage-ways, pump gears submerged in a lubricant in said reservoir to circulate the lubricant through the vertical 75 conduit and passage-ways, means for driving said gears, said means being adapted to extend through the surface of the lubricant in said reservoir, and means associated with said driving means to permit escape of air 80 when said driving means is rotated through the surface of the lubricant. 85

4. A bearing, a casing integral therewith forming a reservoir and provided with passage-ways communicating with said bearing, 90 a cover for said casing extending across the end of said bearing and serving as one side wall for said reservoir and provided with a vertical conduit communicating with said reservoir and said passage-ways, pump gears 95 submerged in a lubricant in said reservoir, a drive gear partly submerged and meshing with one of said pump gears, means for driving said drive gear to cause said pump gears to rotate and force the lubricant from 100 said reservoir to said passage-ways, and collars associated with said drive gear to permit the escape of air when said gear is driven through the lubricant. 105

5. A bearing, a casing integral therewith forming a reservoir and provided with passage-ways communicating with said bearing, a cover for said casing serving as one wall for said reservoir and provided with a conduit communicating with said reservoir and said passage-ways, pump gears submerged in a lubricant in said reservoir, and means for driving said pump gears whereby the lubricant is forced through said conduit and said passage-ways for lubricating said 110 bearing. 115

In witness whereof, I hereunto subscribe my name this 1st day of May A. D., 1922.

CHARLES C. BARBER.
